UNITED STATES PATENT OFFICE.

SAMUEL BLYE, OF BOWLING GREEN, KENTUCKY.

FLOOD-FENCE.

1,161,375.

Specification of Letters Patent.

Patented Nov. 23, 1915.

Application filed January 6, 1914, Serial No. 810,616. Renewed September 8, 1915. Serial No. 49,610.

To all whom it may concern:

Be it known that I, SAMUEL BLYE, a citizen of the United States, residing at Bowling Green, in the county of Warren and 5 State of Kentucky, have invented certain new and useful Improvements in Flood-Fences, of which the following is a specification.

This invention relates to fences and per-10 tains especially to the class of fences constructed and arranged for flood emergencies, or for low sections of farm land where water usually destroys the ordinary fencing.

The object of the invention is to provide 15 a flood fence construction which shall be capable of operation when water pressure thereon is too great, so as to opening a gap or section of the fence and thereby relieve the fence of water pressure.

20 A further object of the invention is to provide ground posts and fence posts of special construction and coöperation for the purpose of dropping one or more sections of the fence under or by reason of water 25 pressure, and to furnish a socket and post-locking device of novel and peculiar construction and arrangement of parts.

Various other objects, advantages and im-30 proved results will be found in the practical application of the invention hereinafter fully described.

In the accompanying drawings forming 35 part of this application: Figure 1 is a side elevation of a fence section embodying my invention. Fig. 2 is a top view showing two fence panels in dropped position. Fig. 3 is an enlarged sectional view taken on the dotted line *a—a* Fig. 1, with one part of the pair in dropped position.

40 The same reference characters denote the same parts throughout the several views of the drawings.

For the purpose of exemplifying my invention I have shown the fence panels composed of rails 1, and wires 2, but such panels may be wholly of wire, or wholly of rails of various character.

45 The ground posts 3 and 4, are set into the ground in the usual manner. The post 4 constituting the end post of a fence line, and the post 3 being duplicated throughout the length of a fence to form the panels.

The top end of the post 3 has a concavity 5, a pair of side flanges 6, and a back por-55 tion 7. These parts form a socket for

swinging posts 9, hereinafter more particularly referred to. A flange 10, projects vertically from the back portion 7, and forms an abutment for the swinging posts 9. The end posts 4 are of substantially the 60 same construction as the posts 3, but the socket is only half the size of the cavity 5; only one end post being shown.

The swinging end post 11 and all of the 65 swinging posts 9 are of substantially the same construction, except the locking bolt 8 of the posts 11 extend through these posts. The posts 9 are arranged together in one pair for each ground post 3, by means of a bolt 12 having a suitable nut 14. The lower 70 ends of the posts 9 have shoulders 15 and 16, fitting, respectively, over the end of flanged 10 projecting from the back portion 7, and over the side flanges 6 of the post 3. Ears 75 project from the lower end of the posts 9 and are pivoted in the cavity 5 by means of a bolt or pivot pin 18 extending therethrough and through the side flanges 6. The inner face of each of the posts 9 is provided with a groove 19, so that when a pair 80 of the posts are fastened together, as hereinbefore explained, the grooves form a hole for a clamping bolt 21 which also extends through a hole 22 in the abutment or flange 10. Similar bolts 23 are used for clamp- 85 ing the ends posts in the sockets thereof.

It will be seen that by removing the bolts 21 and 8 the fence panels thus unlocked are free to swing on the pivot bolts and drop down to horizontal position. This position 90 is maintained by reason of the edge of the ears engaging the outer edge of the sockets.

I do not wish to limit my invention to any particular shape, size or character of fencing material, nor to confine the invention in its practical construction and application, but reserve to myself the right to make such changes and variations therein as may come within the scope of the appended claim.

Having thus described my invention what I claim as new and desire to secure by Letters Patent is:—

A flood fence comprising a plurality of 105 panels arranged in pairs, posts forming the ends of the panels, a bolt for clamping together the adjacent posts of the panels, ground posts having a socket in which the panel posts are pivoted, an abutment projecting from the sockets, a bolt extending through 110

the adjacent faces of the clamped posts and through the abutment of the socket in which the clamped posts are pivoted, and a bolt extending through the other panel posts and through the socket abutments of the other ground posts, substantially as shown and described.

In witness whereof I hereunto set my hand in the presence of two witnesses.

SAMUEL BLYE.
